CLAIM

The ornamental design for a propane torch, as shown and described.

DESCRIPTION

FIG. 1 is a front perspective view of a propane torch, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a partial enlargement of FIG. 1.

The broken lines in the drawings illustrate the portions of the propane torch, which form no part of the claimed design. The short dash, long dash, short dash lines on FIG. 1 and FIG. 8 depict the bounds of the region taken from FIG. 1 to be enlarged on FIG. 8 and form no part of the claimed design.
